(57) **CLAIM**

We claim the ornamental design for a lighted display container, as shown and described.

DESCRIPTION

FIG. 1 is a top front perspective view of a lighted display container showing our new design;

FIG. 2 is a front elevational view thereof, the rear and side views being identical to the front view;

FIG. 3 is a top view thereof;

FIG. 4 is a bottom view thereof; and,

FIG. 5 is an exploded top front perspective view thereof with the display container shown separated from the base.

The ornamental design of a lighted display container having electronic candles in a base upon which the container sits. In an alternate embodiment the container can contain reflective glass marbles to reflect the light from the electronic candles.
